UNITED STATES PATENT OFFICE.

ROBERT STOREY GOLD, OF TORONTO, ONTARIO, CANADA.

SAFETY DEVICE FOR PLATEN PRINTING PRESSES.

Application filed April 29, 1922. Serial No. 557,362.

To all whom it may concern:

Be it known that I, ROBERT STOREY GOLD, a subject of the King of Great Britain, and a resident of the city of Toronto, in the 5 county of York, in the Province of Ontario, Canada, have invented certain new and useful Improvements in Safety Devices for Platen Printing Presses, of which the following is the specification.

10 My invention relates to improvements in safety devices for platen printing presses and the object of the invention is to provide positive means for absolutely preventing accident to the operator when the hand of the 15 operator is withdrawing the printed sheet and as the press is closing and at the same time provide automatic means whereby the press is only actuated when the operator is in the operating position and it consists es- 20 sentially of the arrangement and construction of parts as hereinafter more particu- larly explained.

Fig. 1 is a front elevation of my device, showing it applied to a platen printing press. 25 Fig. 2 is a side elevation of the parts shown in Fig. 1.

Fig. 3 is a plan view of the parts shown in Fig. 1.

Fig. 4 is a sectional view on line 4-4, 30 Fig. 3.

Fig. 5 is a sectional view on line 5-5, Fig. 2.

In the drawings like characters of reference indicate corresponding parts in each 35 figure.

1 indicates a platen press which is of ordinary construction provided with a stationary member 2 and a movable member 3 between which the sheet of newsprint is inserted and from which such sheet is withdrawn by the hand of the operator. 4 and 5 are a pair of tubular standards spaced apart so as to allow sufficient room for the operator to pass between the same. 6 is a diametric orifice formed in each standard 4 and 5 intermediately of their height. 7 and 8 are post members fitting within the standards 4 and 5 and slidable vertically therein and provided with diametric orifices 9 extending 45 parallel with the face of the press and a diametric orifice 10 extending at right angles to the press. 11 is a flexible breast strap extending between the post members 7 and 8. 12 is an eye bolt extending through each orifice 10 and provided with a wing nut 13. 14 is a triangular member composed either of

twisted wire or separate links connected together at their point of junction and around the base portions 15 of which the ends of the strap 11 are suitably secured so as to hang in 60 broad loop form as clearly indicated in Figs. 1 and 3.

16 are inclined braces extending between each standard 4 and 5 and the floor 17 from which the standards extend. 18 is a sleeve 65 slidable upon each standard 4 and 5 and resting normally upon the cross pin 6 of each standard. Each sleeve 18 is provided with a socket 19 in which the upper end of the corresponding inclined brace 16 is secured. 70

20 are sockets provided with base flanges 21 provided with a perforation 22 through which extends a pin 23 extending into an orifice 24 formed in the floor 17 so as to hold the inclined braces in position. 25 and 26 75 are bearings secured to the floor 17. 27 is a rod mounted in the bearings 25 and 26. 28 is a tread plate secured to the rod 27 at one end and extending crosswise in front of the printing press between the standards 4 and 80 5 and the bases 21 of the braces 16.

The free end of the tread plate 28 is provided with a notched recess 29. 30, 31 and 31^x are bearings also secured to the floor 17 and located on the opposite side of the standards 4 and 5 in alignment with the bearings 25 and 26. 32 is a shaft journaled in the bearings 30, 31 and 31^x. 33 is an arm rigidly secured to the shaft 32 and from which extends a cross pin 34 projecting from each 85 side thereof so as to engage beneath the tread plate 28 at each side of the notched recess 29. 35 is the main shaft of the printing press provided with pulley members 36 and 37 and the driving belt 38. The shaft 32 extends 90 95 at its inner end into proximity to the driving pulleys 36 and 37 and is provided in proximity to such inner end with a slotted arm 39 extending upwardly therefrom. 40 is a standard secured to the floor 17 in proximity 100 to the pulleys 36 and 37. 41 is a shift lever provided with a fork 42 engaging the belt 38 of the press.

The lever 41 is pivotally mounted at 43 upon the standard 40 and is provided at its 105 lower end with a pin 44 engaging the slot of the arm 39. 44^x is a tension spring connected at one end to the shift lever 41 and at the opposite end to a suitable anchoring post 45 secured to the floor.

When the operator is using the press he stands upon the tread plate 28 stepping onto

the tread plate between the posts 7 and 8. The weight of the operator depresses the free end of the plate forcing the arm 33 towards the horizontal and thereby swinging the arm

5 39 outward and downward.

By this means the shift lever 41 is thrown inward on its upper end carrying the belt 38 off the idler pulley 37 onto the operating pulley 36. The press then starts to operate. As 10 the operator feeds each sheet of paper in between the members 2 and 3 of the press he leans against the breast strap 11 which holds his hand in a definite position when placing the paper within the press or withdrawing it 15 therefrom or in other words limits his reach so that he cannot place his arm so far in between the members of the press that it cannot readily be withdrawn.

Also the breast strap prevents any danger 20 of the operator being thrown forward off his balance by any other person coming into contact with him in the narrow isles of a printing shop.

Very serious accidents are very often due 25 to this fact and has often caused the loss of an entire arm of a workman. When the operator has finished his work and steps off the tread plate the spring 44* carries the shift lever 41 back to its normal position 30 and the belt 38 into engagement with the idler pulley 37 thereby stopping the machine so that there can be no danger of accidents occurring when the machine is not actually in operation by anybody passing 35 directly in front of it.

In order to permit of free passage 40 between the machine and the standards 4 and 5 I withdraw the pin 23, raise the braces 16 upward so as to slide the sleeves 45 18 vertically and then swing the braces outward at right angles to the normal position thereby leaving a clear passage between the machine and the standards.

From this description it will be seen that 45 I have devised a very simple device which will absolutely prevent danger to the oper-

ator causing serious accidents and not only that but involving the owners of the printing shop in considerable financial loss due to insurance.

50

Owners of printing shops have been desirous for many years to obtain means to overcome danger to the workmen and the accidents that so often take place but to the present time nothing has yet been found 55 which will produce the result desired and which is simple, efficient and cheap to manufacture.

What I claim as my invention is:

1. A safety device for platen printing 60 presses comprising a pair of standards spaced apart and located in front of the printing press, and a flexible breast strap extending between the upper ends of the standards and adapted to extend across the 65 breast of the operator between the operator and the press so as to form a free forward leaning support for the operator, and means for adjusting the breast strap vertically.

2. A safety device for platen printing 70 presses comprising a pair of tubular standards spaced apart and located in front of a printing press, post members slidably vertically within the tubular standards, means for adjusting the height of the post members therein, and a flexible breast strap extending between the post members to form 75 a leaning support for the operator.

3. A safety device for platen printing 80 presses comprising a pair of standards spaced apart and located in front of the printing press, a flexible breast strap extending between the upper ends of the standards and adapted to extend across the 85 breast of the operator so as to form a leaning support for the operator, inclined braces extending forward of each standard support and swingable horizontally therearound, and means for detachably securing the lower ends of the braces to the floor.

ROBERT STOREY GOLD.
